UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

MECHANICAL MOVEMENT.

No. 920,651.

Specification of Letters Patent.

Patented May 4, 1909.

Application filed October 25, 1902. Serial No. 128,756.

To all whom it may concern:

Be it known that I, FRANCIS H. RICHARDS, a citizen of the United States, residing at Hartford, in the county of Hartford and State of Connecticut, have invented certain new and useful Improvements in Mechanical Movements, of which the following is a specification.

This invention relates to an organization of mechanism designed for bringing to a working position any one of a series of instrumentalities which may thereupon be utilized for performing a particular species of operation.

This invention is designed more particularly for employment in an apparatus or mechanism wherein a series of members is caused to move past a station continuously, but which series of members is capable of being halted with one of the members opposite the station, and subsequently to such arrest permitted to proceed and caused to halt with a different member opposite the station when desired. The members if desired may be instrumentalities for performing operations of various natures, which may be similar in kind but may vary in detail.

The new mechanical movement herein set forth may advantageously be employed in organizations embodying a number of movable instrumentalities or members each capable of coöperating with another device at the working point and wherein it is required that the desired member shall be mechanically selected and that the coöperative device be mechanically actuated.

One of the objects of the invention is to provide a new mechanical movement whereby the desired member may be readily and precisely selected and positioned and the coöperative device actuated at one manipulation of a part of the selecting mechanism and whereby after the coöperation of the member and device the selecting mechanism will release the member and by the movement caused by such release will actuate a detent to maintain the member theretofore selected at position, and if it is desired that the member last employed shall again coöperate with the coöperative device the detent will hold the member at position until the selecting mechanism has relieved it of its duty and resumed a position to hold the member at the working point without appreciable movement of the member, and as often as it is desired to repeat the coöperation of the device

with the member at position the selecting mechanism will relieve the detent and actuate the coöperative device and permit the detent to again detain the member at position.

In the drawings attached to the present specification, there is illustrated a practical application of this new mechanical movement; the instrumentalities or members are shown as type-dies mounted upon a carrier, which is shown as frictionally connected with power-driving means for continuous rotation, but held against rotation with one of the dies in the printing position and in which position it remains as long as that particular die is desired for use. Upon the operation of a selector to differently position the carrier (one selector being provided, in the organization shown, for each type-die) the carrier will shift until the die corresponding with that selector is brought into the printing position.

In the form of my invention here illustrated the carrier is normally held stationary by means of a detent, and upon the operation of a selector the detent withdraws its hold and the carrier is permitted to move forward until arrested by the selector, unless the selector for the die which is in the printing position is actuated, when the detent will be moved from its engagement with the carrier and the selector moved into engagement therewith without an appreciable movement or change of position of the carrier.

In the drawings accompanying and forming part of this specification a form of my invention is shown as applied to a typewriting-machine, wherein—

Figure 1 is a plan view; Figs. 2 and 3 are side views in section showing the device in different positions. Fig. 4 is a plan in section on line x—x of Fig. 3; and Figs. 5 and 6 are detail views of a form of escapement.

The various parts of the device may be mounted upon some suitable framework, designated in a general way by A, and in the present instance comprising a base or floor portion 7 provided with upwardly-projecting side walls 8. The working instrumentalities or members, in the present instance impression devices or type-dies 9, are shown mounted upon a carrier or wheel 10 having projecting upon each side thereof an elongated hub 11. The carrier may be mounted upon a shaft 12 journaled in bearings in the

side frame, which in the present instance are shown as bosses 13. Upon the shaft outside of the frame is freely mounted a pulley 14 between disks 15, 15 splined upon the shaft. 5 Between the pulley and the disks are interposed friction disks 15', 15' whereby the carrier or die-wheel may be frictionally rotated from some source of power, not shown. Suitable jam-nuts 15², 15² may be employed 10 for regulating the friction.

The form of typewriter illustrated herein is that wherein a movable hammer and platen are employed to drive the surface of paper and an ink ribbon against the type-dies. The types 15 are moved into the printing position opposite the platen each time a different character is desired to be employed. The platen indicating the working or printing point in the present instance is designated in a general way 20 by b. The hammer, designated in a general way by c, is shown as comprising a head 16 located at the end of a curved operating rod 16' pivoted at 17 to a bracket 18 rising from the floor of the framework.

25 In the present organization each impression device is shown as having its own positioning stop-finger 19 projecting from one or the other of the hubs of the carrier. The stop fingers are shown as radially projecting. 30 There may be provided for each stop-finger a selector, designated in a general way by d. The series of selectors in the present instance embody upright members 20 provided at their lower ends with hubs 21 which are 35 shown as mounted upon a shaft 22 journaled in the frame of the machine in bosses 23. The hubs serve to space the selectors. Suitable springs, here shown as leaf springs 24, may be employed for normally holding the 40 selectors out of the paths of the fingers.

The forward or initial engaging edge of the selector and the edge or initial engaging end of the arresting fingers may be chamfered or beveled off, as at 19', 20', respectively, for 45 the purpose of permitting the selector to be pushed under the finger when it is desired to repeat the character which has just been printed and thereby compensate for any tendency of the carrier to move forward 50 during the change of detaining devices, whereby the carrier will be repositioned in case any slight movement occurs.

Each selector is shown as operated by a finger-key bearing a character or exponent 55 corresponding with an impression device or die upon the carrier. In the present instance letters of the alphabet are shown as the devices upon the working members or instrumentalities, in the present instance dies. 60 There are, however, for the purpose of illustration herein but sixteen characters employed. It is understood, however, that the drawings herein merely illustrate a tangible form of employing the invention. The various 65 parts of the machine will, of course, be

made in such form as the exigencies of the case may demand. Suitable material and structure of the parts will be determined by the builder.

The key-levers, designated in a general way by 25, are each shown as comprising a finger-key 26 connected with the longer end 27 of a lever loosely mounted by means of spacing hubs 27' upon a shaft 28 journaled in the frame, in the present instance in 75 bosses 29. The shorter arm 30 of each lever is shown as bending downwardly and sidewardly and ending in a cam face 31 for engaging the selector and forcing it into the path of the finger of the hub of the carrier. 80

For the purpose of normally holding the carrier in a stationary position against the impulse of the friction driving-wheel a ratchet-wheel 32 is shown as mounted fast upon the driving-shaft, with which ratchet-wheel 85 engages a pawl, in the present instance shown as comprising one end 33 of a bell-crank lever mounted upon a rock-shaft 34 having bearings in bosses 35 in the side frames. The other arm of the bell-crank lever comprises a 90 pair of arms 36 mounted upon the rock-shaft and projecting forwardly of the machine and connected by a bar 37 projecting under all the key-levers. A suitable leaf spring 38 may be provided for returning the pawl to 95 its normal or engaging position.

For the purpose of actuating the hammer at each depression of a key-lever there is shown as located beneath the key-levers a transverse bar 40 connecting a pair of arms 100 41 secured to a rock-shaft 42 journaled in bosses 43 in the side frames, which arms may be provided with suitable leaf springs 44 for returning them to their normal positions. Shown as projecting rearwardly of the rock- 105 shaft 42 is an arm 45 occupying a position beneath an arm 46 projecting from the lower portion of the shaft to the hammer. Projecting upwardly from the arm 45 is a pin 47 traversing an opening in the arm 46 from 110 the hammer, and interposed between which arms 45 and 46 may be a coil-spring 48. A set-nut 49 may be provided upon the upper end of the pin 47 for purposes of adjustment. A suitable catch may be employed for holding 115 the hammer against the action of the spring until such a time as the full or a predetermined tension has been applied thereto and then release the hammer to the influence of the spring, which catch is shown as comprising a plunger 48' mounted in a boss 49' upon the hammer shaft in the region of the arm 46 and engaging a catch 50 upon the bracket 18. The plunger and the catch may be made with beveled edges to facilitate the 120 engagement thereof. The back end of the plunger is shown as secured to one arm 51 of a bell-crank lever pivoted upon the arm 46; the other arm 52 of the bell-crank lever is in position to be engaged by some portion 125 130

of the arm 45, in the present instance a set-screw 53 and jam-nut 54 effective upon the rise of the arm to trip the catch and permit the hammer to fly forward responsive to the spring. A suitable leaf spring 55 may be employed for returning the plunger to its normal position.

The paper 56 in the present instance is shown as rolled up inside of an open-sided tube or pocket 57 secured to a carriage 58, which is shown as mounted in ways 63 secured to the sides of the frame. The paper is shown as passing between a pair of rollers 59, 60, one of which rollers may be provided 15 with a hand-wheel 61 for moving the paper. The paper is shown as guided out of the machine by a plate 62 and as passing between the type-carrier and the platen.

For the purpose of forming impressions a suitable inking ribbon 63 may be employed, which is shown as wound upon spools 64 mounted at suitable places on the ends of the carriage, the ribbon in the present instance being interposed between the paper 25 and the impression dies.

For the purpose of advancing the carriage in the line of its work a suitable spring 65 is shown secured to some convenient portion of the carriage, in the present instance a pin 30 66 projecting through a slot 67 in the ways, and as secured to some fixed portion of the frame, in the present instance a lug 68 mounted at the end of a sleeve 69 for accommodating the spring when the carriage is toward 35 that end. A suitable escapement may be employed for permitting the carriage to advance step by step to accommodate the printing, and in the present instance a rack 70 is shown as provided upon the lower portion 40 of the carriage. The portion of the escapement for coöperation with the rack is shown as mounted upon a rock-shaft 71, mounted in the present instance in bosses in the frame of the machine, and as comprising a block 45 72 secured to the rock-shaft, to which block is pivoted at 73 a bifurcated head 74 having rigid therewith an arm 75 adapted to engage the teeth of the rack. Pivoted to the arm 75 is shown an arm 76, the pivot passing 50 through a lug or boss 77 on the side of the arm 75. There are shown a pair of pins 79, 80 secured to the movable arm for limiting its movement relatively to the other arm. A suitable spring may be employed, as shown 55 at 81, for returning the movable arm against the fixed arm. For rocking the shaft and oscillating the escapement a depending arm 82 may be secured to the rock-shaft 71 and an arm 83 secured to the rock-shaft 34 of the 60 carrier pawl. The ends of the arms may be connected by a link 84, whereby upon each rise of the key-lever the arms of the escapement device will be oscillated and the fixed arm moved out of contact with the rack and 65 the movable arm carried forward by means

of the impetus of the spring of the carriage for a limited distance only and until its pin 79 engages the arm 75. Upon the depression of the key-lever the escapement will be oscillated back into its former position and the loose dog will move out of the rack and the fixed arm into the tooth of the rack next to that occupied by the loose dog. The loose dog will then be returned by the spring into a position to pass into the tooth occupied by the fixed arm, so that the carriage will be moved forward the space of one tooth upon each release or rise of a key-lever. The carriage may be returned by hand and the head of the escapement will turn on the pivot 73 sufficiently to permit the teeth of the rack to ride past the arms of the escapement.

The operation of the mechanism hereinbefore described is as follows:—Upon the depression of a key-lever the pawl is withdrawn from the rack holding the carriage in a stationary position and the cam face of the key-lever will force the selector into the path of the arresting finger upon the hub corresponding to the selected device upon the carrier. Upon the engagement of the finger with the selector the carrier will be stopped with the selected device opposite the platen. Upon further depression of the key the spring interposed between the arms of the hammer and the actuating arm will be compressed until the catch is tripped by the engagement of the bell-crank lever by the set-screw, when the hammer will fly forward responsive to the spring and carry the platen, the paper and inking ribbon against the type. Upon the release of the key-lever the escapement is oscillated and the carrier moved forward one step or a predetermined distance between the centers of the printed characters. Upon releasing the key the hammer will assume its normal position, the plunger riding past the catch and holding it in position for the next action, and the spring will push the selector from engagement with the finger, but before it has entirely lost engagement therewith the pawl will engage the ratchet-wheel upon the driving-shaft and hold the carrier in a stationary position. If the character is to be repeated the carrier will not be permitted to advance, but the selector will be pushed under the finger before the pawl has released the carrier, so that as often as it is desired to repeat the character the only movements will be the key-lever, changing of detents for holding the type-carrier, the advance of the paper carriage and the action of the hammer.

What I claim as my invention and desire to secure by Letters Patent is—

1. The combination with a plurality of instrumentalities each efficient at a prearranged position, of means for positioning a selected instrumentality and temporarily

holding it at position, and means rendered effective by said positioning and temporary holding means for holding the instrumentality at such position after its release by the 5 said positioning and temporary holding means.

2. The combination with a plurality of instrumentalities severally efficient at a position certain, of means for positioning a selected instrumentality and temporarily holding it at position, and means controlled by the positioning and temporary holding means for holding the instrumentality at such position after its release thereby and until another 10 instrumentality positioning and selecting means has been actuated.

3. The combination with a plurality of instrumentalities each efficient at a prearranged position, of means tending normally 20 to pass the instrumentalities serially into and out of their efficient positions; means for positioning a selected instrumentality and temporarily holding it at position, and means for normally holding all the instrumentalities stationary and the selected instrumentality at such position after the release of the selected instrumentality by the positioning and temporary holding means.

4. The combination with a plurality of instrumentalities each efficient at a prearranged position, of means tending normally 30 to pass the instrumentalities serially into and out of their efficient positions, means for positioning a selected instrumentality and temporarily holding it at efficient position, and means controlled by the positioning and holding means for normally holding all the instrumentalities stationary and the selected instrumentality at such position after the 35 release of the selected instrumentality by the selecting means and until another instrumentality has been selected thereby.

5. In a device of the character specified, the combination with a carrier, working surfaces disposed upon the carrier, a working point for the working surfaces, means tending to normally rotate the carrier and shift the surfaces past the working point, means for normally holding the carrier with one of 45 the surfaces at its working point, and means for determining which surface shall be so held.

6. In a device of the character specified, the combination with a carrier, working devices carried thereby, a working point, means tending to normally shift the carrier and bring the devices to the working point, means for normally holding the carrier stationary and one of the devices at its working point, 50 and means for determining which device shall be so held.

7. The combination with a plurality of working devices, a common working point, means tending to normally shift the devices past the working point, means for normally 55

holding the devices stationary and one of them at the working point, and means for determining which device shall be so held.

8. The combination with a plurality of members efficient at a position certain, of 70 means for moving the members in prearranged order past such position, a series of fingers for the members, a series of fingers co-operative with one series of member fingers, means for actuating the co-operative fingers 75 to position the members, and means actuated by the release thereof adapted to engage the finger for the same member from the other series and to maintain the member in such position until the actuation of a co-operative finger for another member. 80

9. The combination of a series of impression devices, means for shifting the series and bringing the devices into and out of their working positions, means for normally maintaining the series stationary and the device last employed at its working position, means for determining which device shall come into the working position, and means for withdrawing the maintaining means and permitting the series to shift if a new device is to be employed and to remain stationary if the device at the working point is to be employed. 85

10. The combination of a series of impression devices, a carrier therefor, means for 95 shifting the carrier and bringing the devices into and out of their working positions, means for normally maintaining the carrier stationary and one of the devices in its working position, means for determining which device 100 shall be maintained at the working position, and means for withdrawing the maintaining means and permitting the carrier to shift to bring another device into its working position. 105

11. The combination of a plurality of instrumentalities for performing operations similar in kind but differing in detail, a carrier therefor, means tending to shift the carrier, a selector for each instrumentality constructed and adapted for stopping the carrier with the selected instrumentality at a common fixed working point, and means controlled by the selectors when operated for maintaining the carrier in its position determined by the selector last operating upon it until a different selector is brought into action. 110

12. The combination with a plurality of dies, of means for positioning a selected die 120 and temporarily holding it at its working position, and a ratchet and pawl controlled by the positioning and holding means for holding the die at its working position after its release by the positioning and holding means. 125

13. The combination with a plurality of dies, of a carrier therefor, stop faces upon the carrier for each of the dies, a selector co-operating with the stop faces for positioning and temporarily holding at position each die, and 130

a ratchet and pawl controlled by the selector-actuating means for holding the die at its working position after it is released by the selector.

5. 14. The combination with a plurality of dies, of a carrier therefor, hubs upon the carrier, a stop face upon the hubs for each of the dies, means for shifting the carrier, a selector coöperative with each of the stop faces 10 for positioning and temporarily holding at its working position each die, and means for holding the die at such position after it is released by the selector.

15. The combination with a plurality of dies, of a carrier therefor, hubs upon the carrier, a stop face upon the hubs for each of the dies, means for shifting the carrier, a selector coöperative with each of the stop faces for 20 positioning and temporarily holding at its working position each die, and a ratchet and pawl controlled by the selector-actuating means for holding the die at its working position after it is released by the selector.

16. The combination with a rotary die 25 carrier, of dies disposed thereon, a stop face upon the carrier for each of the dies, means arranged for interposition into the path of the stop faces, means for actuating the interposing means, a ratchet wheel having a tooth 30 for each die rigid with the carrier, and a pawl controlled by the actuating means for engaging the ratchet-wheel prior to the release of the stop faces.

17. The combination with a rotary die 35 carrier, dies arranged upon the periphery thereof, hubs projecting laterally from the carrier, a detent from the hubs for each of the dies, a shaft for the carrier, friction driving means upon the shaft, a selector for each die, 40 means for advancing the selectors to engage the detents, a ratchet-wheel upon the shaft having a tooth for each die, a pawl for engaging with the ratchet-wheel, and means operable by the advancing means for withdrawing 45 the pawl from the ratchet-wheel upon the actuation of a selector and for permitting the same to engage the wheel upon the release of the detent by the selector.

18. The combination with a plurality of 50 movable members, of a device organized to coöperate at a fixed working point with the respective members, means for causing the members to pass the working point, means for arresting any member at the working 55 point, means actuated by the arresting means for causing the device to coöperate with the arrested member, and means controlled by the arresting means for holding such member at the working point until 60 means have been actuated to arrest a different member.

19. The combination with a plurality of 65 members, of means for bringing the members serially into a fixed position, means for stopping each member at such position and inci-

dentially the other members at whatever position they may be in, a device coöperative in the performance of its function with the member so stopped, means operated by the stopping means for actuating the coöperative 70 device, means independent of the stopping means for normally holding all the members stationary and the member last brought to position at such position, means for withdrawing the holding means upon the actuation of the stopping means, which stopping means is organized to hold at the said fixed 75 position the member last stopped if such member is to be reëmployed, and to stop the member desired if a new one is to be employed 80 upon its first coming into the position after the actuation of the stopping means therefor.

20. The combination with a plurality of 85 instrumentalities, a detent coöperative therewith at a position certain, of means for positioning a selected instrumentality and temporarily holding it at such position, means for holding the instrumentality at such position after its release by the positioning means, and controlled by the positioning and 90 selecting means upon its actuation to render the coöperation of the device effective.

21. The combination with a plurality of 95 instrumentalities severally efficient at a position certain, of means for positioning a selected instrumentality and temporarily holding it at such position, means controlled by the positioning and temporary holding means for holding the instrumentality at position 100 after its release by said positioning and temporary holding means and until another instrumentality positioning and selecting means has been actuated, means coöperative with the instrumentality when at position, and means actuated by the positioning and 105 selecting means for rendering the coöperation effective.

22. The combination with a plurality of 110 instrumentalities, each efficient in coöperation with some other device at a prearranged position, a device coöperative therewith, means tending normally to pass the instrumentalities serially into and out of their efficient positions, means for positioning a selected instrumentality and temporarily 115 holding it at efficient position and actuating the coöperative device, and means for normally holding all the instrumentalities stationary and the selected instrumentality at efficient position after the release of the 120 selected instrumentality by the positioning means.

23. The combination with a movable device, of a plurality of work-performing members, each efficient in coöperation with the 125 device at a prearranged position, means tending normally to pass the members serially into and out of their efficient positions, means for positioning a selected member and temporarily holding it at effective position and 130

for moving the movable device to coöperate with the selected member, and means controlled by the positioning means for normally holding all the members stationary and the selected member at such efficient position after the release of the selected member by the selecting and holding means and until another member has been selected thereby.

24. In a device of the character specified, the combination with a carrier, working surfaces disposed upon the carrier, a device coöperative with the working surfaces at a working point, means tending to normally rotate the carrier and shift the surfaces past the working point, means for normally holding all the members stationary and the selected member at position at the working point after the release of the selected member by the selecting means and until another member has been selected thereby.

25. In a device of the character specified, the combination with a carrier, working members carried thereby, a coöperative working device, means tending to normally shift the carrier and bring the members to the working point of the device, means for normally holding all the members stationary and the selected member at position at such working point after the release of the selected member by the selecting holding means and until another member has been selected.

26. The combination with a movable device, of a plurality of members coöperative therewith at a position certain, means for moving the members in prearranged order past such position, two series of detents for the members, a series of detents coöperative with one series of member detents, means for actuating the coöperative detents to position the members at such position certain and actuate the movable device, and means actuated by the release thereof adapted to engage the detent for the same member from the other series of member detents and to maintain the member in such position until the actuation of a coöperative detent for another member.

27. In a device of the character specified, the combination with a carrier, working surfaces disposed upon the carrier, a working point for the working surfaces, means embodying a shaft upon which the carrier is mounted, a pulley loose upon the shaft, and friction connections between the shaft and pulley, tending to normally rotate the carrier and shift the surfaces past the working point, means for normally holding all the members stationary and the selected member at position after the release of the selected member by the selected holding means and until another member has been selected thereby.

28. In a device of the character specified, the combination with a carrier, working devices carried thereby a working point, means embodying driving means having frictional

connection with the carrier, tending to normally shift the carrier and bring the devices to the working point for normally holding all the members stationary and the selected member at position after the release of the selected member by the selected holding means and until another member has been selected thereby.

29. The combination with a plurality of dies, of a carrier therefor, a shaft upon which the carrier is mounted, driving means mounted upon the shaft, frictional connections whereby the drive from the driving means is yieldingly imparted to the carrier, stop faces upon the carrier for each of the dies, a selector coöperating with the stop faces for positioning and temporarily holding at position each die, and a ratchet and pawl controlled by the selector-actuating means for holding the die at its working position after it is released by the selector.

30. The combination with a plurality of dies, of a carrier therefor, hubs upon the carrier, a stop face upon the hubs for each of the dies, means for shifting the carrier, embodying a shaft upon which the carrier is mounted, a pair of friction faces fast upon the shaft, a pair of friction disks loose upon the shaft between the faces, a pulley loose upon the shaft between the disks, and means for adjusting the frictional engagement, a selector coöperative with each of the stop faces for positioning and temporarily holding at its position each die, and a ratchet and pawl controlled by the selector-actuating means for holding the die at its working position after it is released by the selector.

31. The combination with a rotary die carrier, dies arranged upon the periphery thereof, hubs projecting laterally from the carrier, a detent from the hubs for each of the dies, a shaft for the carrier, friction driving means upon the shaft, a selector for each die, a shaft upon which the selectors are mounted, a hub on each selector surrounding the shaft and spacing the selectors, a lever for each selector, a shaft upon which the levers are mounted, a hub on each lever surrounding the shaft and spacing the levers, a cam face upon each lever for advancing the selectors to engage the detents, a ratchet-wheel upon the shaft having a tooth for each die, a pawl for engaging the ratchet-wheel, and means embodying a rock-shaft upon which the detent is mounted, arms projecting from the rock-shaft, a bar disposed in the path of movement of the levers connecting the ends of the arms, for withdrawing the pawl from the ratchet-wheel upon the actuation of a selector and for permitting the same to engage the wheel upon the release of the detent by the selector.

32. The combination with a rotary die carrier, dies arranged upon the periphery thereof, hubs projecting laterally from the

carrier, a detent from the hubs for each of the dies, a shaft for the carriage, friction driving means upon the shaft, a selector for each die, a shaft upon which the selectors are mounted, a hub on each selector surrounding the shaft and spacing the levers, a cam face upon each lever for advancing the selectors to engage the detents, a ratchet-wheel upon the wheel having a tooth for each die, a pawl for engaging the ratchet-wheel, means, embodying a rock-shaft upon which the detent is mounted, arms projecting from the rock-shaft, a bar disposed in the path of movement of the levers connecting the ends 15 of the arms, for withdrawing the pawl from the ratchet-wheel upon the actuation of a selector and for permitting the same to engage the wheel upon the release of the detent by the selector, a carriage for carrying impression material past the working point of the dies, means tending to move the carriage, a rack carried by the material carriage, a rock-shaft adjacent thereto, means controlled by the levers for operating the rock-shaft, and 20 means carried by the rock-shaft and organized to engage the rack and permit the advance of the material carriage, step by step, and embodying a block fast upon the rock-shaft, a head pivoted to the block normally held from movement in the direction of movement of the material carriage, a finger rigid with the 25 block and a finger pivoted to the rigid finger and free to move the distance of one tooth of the rack in such direction, a spring for positioning the free finger, and pins on the free finger to limit its movement relatively to the 30 rigid finger.

33. The combination with a rotary die carrier, dies arranged upon the periphery 40 thereof, hubs projecting laterally from the carrier, a detent from the hubs for each of the dies, a shaft for the carrier, friction driving means upon the shaft, a selector for each die, a shaft upon which the selectors are 45 mounted, means for spacing the selectors, a lever for each selector, a shaft upon which the levers are mounted, means for spacing the levers, a cam face upon each lever for advancing the selectors to engage the detents, a 50 ratchet-wheel upon the wheel having a tooth for each die, a pawl for engaging the ratchet-wheel, means, embodying a rock-shaft upon which the detent is mounted, arms projecting from the rock-shaft, a bar disposed in the 55 path of movement of the levers connecting the ends of the arms, for withdrawing the pawl from the ratchet-wheel upon the actuation of a selector and for permitting the same to engage the wheel upon the release of 60 the detent by the selector, a carriage for carrying impression material past the working point of the dies, means organized to bring the impression material and selected die into working engagement and embodying a hammer, a 65 pivoted haft upon which the hammer

is mounted, a rock-shaft adjacent thereto, means actuated by the levers to rock the shaft upon the selection of a die, an arm projecting from the haft, a spiral spring impinging against said arm, a pin secured to one arm and traversing the other arm and the spring, a set-nut upon the pin, a stationarily-disposed detent, a catch co-operative therewith, a plunger mounted upon the haft and carrying the catch, a bell crank pivoted to the haft and connected by one arm to the plunger, and an adjustable lug carried by the rock-shaft arm for engaging the other arm of the bell crank, means tending to move the material carriage, a rack carried by the material carriage, a rock-shaft adjacent thereto, means connected to the pawl for operating the rock-shaft, and means carried by the rock-shaft and organized to engage the rack and permit the advance of the material carriage, step by step, and embodying a block fast upon the rock-shaft, a head pivoted to the block normally held from movement in the direction of movement of the material carriage, a finger rigid with the block and a finger pivoted to the rigid finger and free to move the distance of one tooth of the rack in such direction, a spring for positioning the free finger, and pins on the free finger to limit its movement relatively to the rigid finger.

34. The combination with a plurality of dies, of a selector for each die, a lever for advancing each selector, a carriage for carrying impression material past the working point of the dies, means organized to bring the impression material and selected die into working engagement and embodying a hammer, a pivoted haft upon which the hammer is mounted, a rock-shaft adjacent thereto, means actuated by the levers to rock the shaft upon the selection of a die, an arm projecting from the haft, a spiral spring impinging against said arm, a pin secured to one arm and traversing the other arm and the spring, a set-nut upon the pin, a stationarily-disposed detent, a catch co-operative therewith, a plunger mounted upon the haft and carrying the catch, a bell crank pivoted to the haft and connected by one arm to the plunger, and an adjustable lug carried by the rock-shaft arm for engaging the other arm of the bell-crank, means tending to move the material carriage, a rack carried by the material carriage, a rock-shaft adjacent thereto, a pawl, means connected to the pawl for operating the rock-shaft, and means carried by the rock-shaft and organized to engage the rack and permit the advance of the material carriage, step by step, and embodying a block fast upon the rock-shaft, a head pivoted to the block normally held from movement in the direction of movement of the material carriage, a finger rigid with the block and a finger pivoted to the rigid finger.

and free to move the distance of one tooth of the rack in such direction; a spring for positioning the free finger, and pins on the free finger to limit its movement relatively to the rigid finger.

35. In a device of the character specified, the combination with an impression device, a shiftable carriage for carrying material past the working point of the device, means tending to move the carriage, means arranged to actuate the impression device and cause the same to impress itself upon the material, a rack carried by the carriage, a rock-shaft adjacent thereto, means controlled by the impression-actuating means for operating the rock-shaft, and means carried by the rock-shaft and organized to engage the rack and permit the advance of the carriage, step by step, and embodying a block adjustable upon the rock-shaft, a head pivoted to the block normally held from movement in the direction of movement of the carriage, a finger rigid with the block and a finger pivoted to the rigid finger and free to move the distance of one tooth of the rack in such direction, a spring for positioning the free finger, and pins on the free finger to limit its movement relatively to the rigid finger.

36. In a device of the character specified, the combination with a series of impression devices, a carrier therefor, hubs upon the carrier, a stop face upon the hubs for each impression device, a selector for engaging each stop face, means for advancing the selectors, a ratchet-wheel rigid with the carrier and having a tooth for each impression device, a pawl for engagement with the ratchet-wheel, means controlled by the advancing means for actuating the pawl, a platen, means for advancing the platen toward the impression devices, means controlled by the selector-advancing means for releasing the platen-advancing means, a carrier for supporting an impressionable surface, a rack upon the carriage, a rock-shaft adjacent thereto, a fixed and movable finger upon the rock-shaft adapted to engage the teeth of the rack and permit the carriage to advance step by step, a link connecting the rock-shaft and the pawl, and means for advancing the carriage.

37. The combination with a plurality of instrumentalities severally efficient at a position certain, of means for positioning a selected instrumentality and temporarily holding it at such position, means controlled by the positioning means for holding the in-

strumentality at such position after its release thereby and until another instrumentality positioning and selecting means has been actuated, a hammer coöperative with the instrumentalities at position, a pivoted haft upon which the hammer is mounted, a rock-shaft adjacent thereto, means actuated by the positioning and selecting means to rock the shaft upon the selection of an instrumentality, an arm projecting from the haft, an arm projecting from the rock-shaft, a spring therebetween, a pin secured to one arm and traversing the other arm, a tension device for the spring, a stationarily-disposed detent, a catch coöperative therewith, a plunger mounted upon the haft and carrying the catch, a bell crank pivoted to the haft and connected by one arm to the plunger, and an adjustable lug carried by the rock-shaft arm for engaging the other arm of the bell-crank.

38. The combination with a rotary die carrier, of dies disposed thereon; a stop face upon the carrier for each of the dies, means arranged for interposition into the path of the stop faces, means for actuating the interposing means, a ratchet-wheel having a tooth for each die rigid with the carrier, a pawl controlled by the actuating means for engaging the ratchet-wheel upon the release of the stop faces, a carriage for carrying impression material past the working point of the dies, means tending to advance the carriage, a rack carried by the carriage, a rock-shaft adjacent thereto, a pawl, means connected to the pawl for operating the rock-shaft, and means carried by the rock-shaft and organized to engage the rack and permit the advance of the carriage, step by step, and embodying a block fast upon the rock-shaft, a head pivoted to the block normally held from movement in the direction of movement of the carriage, a finger rigid with the block, a finger pivoted to the rigid finger and free to move the distance of one tooth of the rack in such direction, a spring for positioning the free finger, and pins on the free finger to limit its movement relatively to the rigid finger.

Signed at Nos. 9-15 Murray street, New York, N. Y., this 24th day of October, 1902.

FRANCIS H. RICHARDS.
